UNITED STATES PATENT OFFICE

151,975

DESIGN FOR A DUPLICATING MACHINE

Arthur H. Geib, Milwaukee, Wis.

Application May 13, 1947, Serial No. 139,019

Term of patent 7 years

(Cl. D64—11)

To all whom it may concern:

Be it known that I, Arthur H. Geib, a citizen of the United States, residing at Milwaukee, in the county of Milwaukee and State of Wisconsin, have invented a new, original, and ornamental Design for a Duplicating Machine, of which the following is a specification, reference being had to the accompanying drawings, forming part thereof.

In the drawing:

Figure 1 is a perspective view of a duplicating machine, in its closed position, looking towards the crank side and front or feed end thereof, showing my new design.

Figure 2 is a side elevation of the duplicating machine, in open position, looking towards the crank side of the machine.

Figure 3 is a perspective view of the duplicating machine, in closed position, looking towards its front end and that side thereof opposite its crank side.

Figure 4 is an elevation of my new design of duplicating machine, in open position, looking towards that side of the same opposite its crank side.

Figure 5 is a top plan view of the duplicating machine, in its open position.

Figure 6 is a front end elevation of the duplicating machine, in open position, looking towards its feed end, and

Figure 7 is a rear end elevation of the duplicating machine, in open position, showing the discharge end of the said machine.

I claim:

The ornamental design for a duplicating machine, as shown and described.

ARTHUR H. GEIB.
